UNITED STATES PATENT OFFICE.

JOHN S. WORTH, OF COATESVILLE, PENNSYLVANIA.

MACHINE FOR CUTTING ELLIPTICAL HOLES.

SPECIFICATION forming part of Letters Patent No. 655,538, dated August 7, 1900.

Application filed December 31, 1897. Serial No. 664,935. (No model.)

To all whom it may concern:

Be it known that I, JOHN S. WORTH, a citizen of the United States, and a resident of Coatesville, Pennsylvania, have invented certain Improvements in Machines for Cutting Elliptical Holes, of which the following is a specification.

My invention relates especially to machines for cutting elliptical holes in metallic plates, such as boiler and tank plates; but it will be understood that the machine can be constructed for cutting elliptical holes in other materials and for other purposes as well.

The object of my invention is to simplify the construction of a machine for cutting elliptical holes, to make it adjustable, and to so arrange the tool-carrier that the tool will cut either an elliptical hole or a round hole, as fully set forth hereinafter.

In the accompanying drawings, Figure 1 is a side view of my improved machine for cutting elliptical holes. Fig. 2 is a section on the line 2 2, Fig. 1. Fig. 3 is an end view looking in the direction of the arrow 3, Fig. 1. Fig. 4 is a view of a modification, and Fig. 5 is a view showing the tool arranged on a different type of support from that shown in Fig. 1.

Referring to Figs. 1, 2, and 3, A is the base of the machine, having a standard A'. On the face of this standard are slideways a a, on which slides vertically the carrying-arm B, having slideways b b for the tool-carriage D.

Fixed on the arm B is a bracket E, in which is mounted a shaft e, having on one end a head e', in which is mounted a slide e², carrying a stud e³. The slide e² is adjusted in the head e' by set-screws e⁴, one bearing against each end of the slide. By adjusting the set-screws more or less throw is given to the stud e³. The stud e³ is connected to the carriage D by means of a rod F, so that as the head e' revolves the carriage D is reciprocated on the slideways b b. The carriage D carries the driven tool-shaft d, having at its lower end a tool-head d', in which is mounted a tool d² of any suitable form. The tool-head can be made in the usual manner, so that the tool can be adjusted toward or from the center of rotation to cut smaller or larger holes. As the tool-shaft revolves and the carriage reciprocates on its slide the tool travels in the

path of an ellipse, and by increasing the movement of the carriage or adjusting the tool holes of different shape and size may be cut. 55

I is the driving-shaft, mounted in suitable bearings in the base of the machine, and on this shaft are the belt-pulleys i. The shaft I is geared to the shaft I' by bevel-wheels i'. The shaft I' is splined in the present instance, 60 and adapted to slide on the shaft is a bevel-wheel i², gearing with a wheel i³ on a shaft I². The shaft I² is adapted to bearings in the bracket E and carriage D, and on the shaft is a bevel gear-wheel i⁴, which meshes with a bevel-wheel e⁵. On the hub of this wheel is a gear-wheel e⁶, which meshes with a gear-wheel e⁷ on the shaft e. Through these gears motion is given to the shaft e and its head e'. The outer end of the shaft I² is splined, and 70 on the shaft is a bevel gear-wheel i⁵, having a feather resting in the spline, so that while it will turn with the shaft it slides with the carriage D. The bevel-wheel i⁵ meshes with a bevel-wheel d². On the hub of this wheel 75 is a gear-wheel d⁴, which meshes with a wheel d⁵, having a feather adapted to the splined tool-shaft d, so that while the tool-shaft will turn with the gear it can be also raised or lowered to the work. Any means may be 80 used to adjust the tool. I have shown a common form of adjusting mechanism consisting of a rack f, forming a continuation of the tool-shaft, and a pinion f', meshing therewith and mounted on a shaft f², on which is a hand-wheel f³, on turning which the tool may be 85 raised or lowered.

The carrying-arm B may be raised or lowered by a screw-shaft K, adapted to a bearing in the frame of the machine and to a nut 90 in the carrying-arm B. This screw-shaft can be turned by hand or by power.

After the machine is set by adjusting the tool d² and the slide e² in the head e' the plate or other article is secured to the table A², 95 which is mounted on the base-plate, and the machine set in motion. As the tool revolves around its center of rotation it is also moved toward and from the center by the head e' through the rod F, and thus it travels in an 100 elliptical path, cutting the hole in the plate the desired form and size.

It will be understood that the construction and arrangement of the supporting-frame

may be modified without departing from the main feature of my invention. For instance, instead of having the carriage mounted on a projecting arm, as shown in Fig. 1, the carriage 5 may be secured to a bar adapted to slide in standards at each end of the machine and this bar itself reciprocated by means of the crank on the shaft at one side of the machine, as shown in Fig. 4.

10 In Fig. 5 I have shown a series of drill-heads on a cross-frame secured to end standards. The heads D' are ordinary drill-heads which may be adjusted at any point on the frame, while the head D is connected to a 15 crank in the same manner as shown in Fig. 1. This head D can be disconnected from its crank and secured to the frame, so that it can be used to cut circular holes. The head D, Fig. 1, may be also disconnected and secured to the arm B for the same purpose. In 20 the present instance I have shown a series of set-screws s, which can be turned so as to confine the head D to the arm B. By backing off these screws the head can be released.

25 I claim as my invention—

1. The combination in a machine for cutting elliptical holes, of the carrier, a head thereon, a tool-shaft mounted in said head, an arm on said shaft carrying a tool, means 30 for driving the tool-shaft, a driven shaft, a head thereon, a slide mounted on said head, a stud carried by said slide, a rod connecting

the said stud to the head and set-screws bearing against each end of the slide for adjusting the slide, substantially as described.

2. The combination of a base adapted to receive material to be cut, a standard, an arm vertically adjustable on the standard, a bracket fixed on the arm, a shaft mounted on the bracket, an adjustable crank carried by 40 the shaft, a carriage adapted to slide on the arm, a tool-shaft mounted in the carriage, an arm on the shaft carrying a tool, a rod connecting the adjustable crank to the carriage, a driven shaft geared to the crank-shaft and 45 the tool-shaft so that as the tool-shaft is rotated the carriage will be reciprocated, substantially as described.

3. The combination in a machine for cutting elliptical holes, of the frame, a fixed shaft 50 having an adjustable crank, a sliding carriage, a tool-shaft thereon, means for connecting the adjustable crank to the tool-carriage and means for fastening the tool-carriage in a fixed position when detached from 55 the crank-shaft so that the tool can cut circular holes, substantially as described.

In testimony whereof I have signed my name to this specification in the presence of two subscribing witnesses.

JOHN S. WORTH.
